UNITED STATES PATENT OFFICE

ALFRED G. F. KUROWSKI, OF BROOKLYN, NEW YORK, ASSIGNOR TO UNDERWOOD
ELLIOTT FISHER COMPANY, OF NEW YORK, N. Y., A CORPORATION OF DELAWARE

TYPEWRITING MACHINE

Application filed June 5, 1924. Serial No. 717,994.

This invention relates to typewriting machines, and is herein disclosed as applied to an Underwood portable typewriting machine wherein the typing elements are mounted 5 upon a stationary support, and the platen is mounted on a carriage.

A feature of this invention is the provision of guide-rollers to engage the end-plates of the shift-frame to eliminate vibration resulting from letter-feeding movements of the carriage, thus preventing blurred printing, which may otherwise result from this cause.

Another feature provides a novel arrangement whereby the whole carriage structure 15 may be readily removed from the frame without dismounting other parts of the machine, thus saving much time when desirous of repairing or adjusting parts of the mechanism ordinarily inaccessible when the carriage is 20 in place.

Another feature includes the provision of a shift-key lever, one end of the lever being arranged to act against means associated with the lower portion of the shift-frame, to throw 25 said frame to upper-case position with a comparatively light and easy pressure upon the shift-key.

This application discloses a case-shift-frame adjusting or truing means identical 30 with that disclosed in my application Serial No. 699,420, filed March 15, 1924, now Patent No. 1,673,687, dated June 12, 1928.

Other features and advantages will hereinafter appear.

35 In the accompanying drawings,

Figure 1 is a left-hand side elevation of the typewriting machine, with portions broken away, and other parts omitted.

Figure 2 is a plan view of the extreme left-hand section of the machine indicating a portion 40 of the carrying case in dot-and-dash lines.

Figure 3 is a side view of the carriage-shifting frame, showing its link connection to the frame of the machine.

45 Figure 4 is a fragmentary view looking

from the front of the machine, showing the carriage-counterbalancing spring and its connections.

Figures 5 and 6 are detail views of parts of the mechanism.

Figures 7 and 8 are details of the eccentric adjustments of the carriage shift arms.

In the illustrated embodiment of the invention, 10 indicates a complement of key-levers arranged in four banks as customary for a standard keyboard, each key-lever operating a bell-crank 11 that swings on a fulcrum wire 12 to operate a connection 13 linked to a type-bar 14 arranged to throw the type-bar to the printing position at a platen 15. 55 Each type-bar is provided with two type-faces and pivoted to a slotted segment 16 fixed to the frame 16' of the machine. The platen 15 is provided with a traveling carriage 17 mounted on a shift-frame 18 comprising end-plates 18' joined together by a back plate 19 having ears 20 that are riveted to said plate, as indicated at 20'. This three-sided shift-frame 18 is hung or suspended from the forward ends of two links 21 and 22 arranged at 60 each side of said shift-frame. A reinforcing plate 23 may be arranged to face against the inner side faces of the frame 16' and be secured thereto by means of suitable screws, as shown.

75 Each of the links 21 and 22 is so connected that each may be adjusted forward or back independently of all the other links. For this purpose one end of each link is mounted upon an eccentric pivot which is adjustable 80 to change the eccentricity thereof. In the present instance the eccentric pivot connecting the links with the main frame is shown particularly in Figure 8. The link 21 is connected to the main frame by a pivot 24 having an annular groove 25 intermediate its ends 85 engaged by a set-screw 26 threaded through the main frame. This screw prevents longitudinal movement of the pivot, while permitting rotation thereof, and it is turned by 90

means of a hexagonal head 27, the link 21 being mounted on an eccentric portion 28 of the pivot which is between the head 27 and the body of the pivot 24. The pivot 29, which connects the link 22 with the main frame, is journaled in an opening in the main frame, and said pivot has an annular groove 30 engaged by a set-screw 31 to rotatably connect the same with the main frame. The link 22 is journaled on a reduced portion of a rock-shaft 32 between the shoulder formed by said reduced portion and the adjacent side of the frame 16'. When either pivot 24 or 29 is turned, the eccentric portion thereof is shifted angularly, and the effective length of the adjacent link, that is, the distance between the axes of its pivots is changed. Thus to move the shift-frame toward or from the typing system, the ends of the shift-frame may be simultaneously or independently moved, as may be desired. Also the frame may be adjusted angularly, and it may be tilted forwardly or rearwardly by increasing or diminishing the effective length of the links 21 or the links 22.

This adjustable connection between the main frame and the carriage shift-frame permits an exact positioning of the carriage with respect to the segment 16, so that the platen-printing line may be brought into coincidence with the printing plane of the type-faces, and without the necessity for any change in the position of the segment. The links 21 are curved upwardly and forwardly to pass under the carriage, and the free ends secured with a shouldered screw 21' threaded into the end-plates 18'. The links 22 include hubs 33 pinned to the rock-shaft 32, which, in the interest of lightness in structure, comprises a tube hung at each end upon the pivot 29 provided in each side of the frame 16'. The forward ends of the links 22 support a fixed stud 34 that is reduced at the free end to receive a roller 35 held thereon by a screw 36 threaded into the end of the stud. This stud 34 forms a second support for the end plates 18' by entering an open slot 37 formed in the lower edge of the plates and held against accidental displacement by a latch 38 mounted to swing upon a pivot screw 39, and bear against the inside face of the plates 18'. An open slot 34' in the latch 38 is arranged to engage with the stud 34 to lock it in operative position within said slot, or to release the stud so that the carriage-frame may be disengaged from the links 22 and lifted clear of the machine. The locking or release position of the latch 38 may be made permanent by a set-screw 40 operating within a circular groove in the latch and acting to clamp the latch to the face of the plates 18'. A finger-piece 38' provides means whereby the latch 38 may be readily shifted.

In order to provide a free and accurate up-and-down movement of the carriage, an anti-friction roller 41 is mounted between ears

42 forming part of brackets 43 fixed to the lower edge of the frame 16' at the two sides of the machine. Each bracket extends inwardly under the links 22, and is then curved upwardly to bring its roller against the inside face of the adjacent end plate 18'. Hence the up-and-down movement of the carriage is guided by the contact of the plates 18', and the rollers 41 on the inside of the shift-frame. Numeral 44 indicates a tongue secured to each plate 18' and formed with a bent-over end to provide a stop element 45. This stop element shifts with the frame and limits its movement in two directions through abutment with a pair of oppositely-disposed adjustable stops 46 and 47 mounted upon adjacent parts of the stationary frame 16'.

In the normal position of the carriage, where the printing line is in alignment with the lower-case type or small letters, the stop element 45 of the carriage-frame will rest upon the lower adjustable stop 47 through the weight of the carriage and its associated parts. This dead weight is usually so great as to promote a hard carriage-shifting movement of the shift-keys indicated at 56, and it is the usual practice to provide counterbalancing elements to relieve the shift-keys of most of this burden. To this end the rock-shaft 32 is provided with a spiral spring 48 having one end secured, in any suitable manner, to a bracket 49 fixed to the back frame 50 of the machine, and the opposite ends secured to a sleeve 51 adjustably mounted upon said shaft and formed with ratchet crown teeth 52 adapted to interlock with similar teeth 53 in a collar 54 pinned to the shaft.

The spring 48 tends to hold the teeth of sleeve 51 and collar 54 in engagement with each other and also reacts through the shaft 32 to raise the forward ends of the links 22 and lift the carriage away from the lower stop 47. The extent of this lifting power of the spring is determined by the tension given the spring by turning the sleeve 51 to wind or unwind the coils, and any adjustment may be made permanent by a set-screw 55. One shift-key 56 is usually provided adjacent each side of the keyboard, so that shifting of the carriage may be accomplished by either hand. This shift-key, contrary to the usual practice, does not extend rearwardly the full depth of the machine similarly to the key-levers, but is fulcrumed to the side frame as at 57, providing a lever of the first order. The shift-key, at the forward end, has the same general contour as the key-levers in the first or lower bank and extends rearwardly, where the free end 56' passes under the roller 35 of the stud 34. Said roller operates against a cam-face formed in the edge of the end 56', and enables an operator to raise the platen and carriage by a comparatively light and easy pressure upon the shift-key. Each shift-key 56 may be provided with a spring

57' connected to some part of the frame, as indicated at 58, the spring acting to hold said key in its normal position against a stop-plate 59 secured to the inside face of a front comb 60.

61 is a shift-lock key-lever pivotally hung from a stud 62 on the face of the shift-key 56 directly at the rear of the comb 60. The shift-lock lever 61 is provided with a spring 63 connecting said lever with an ear 64 formed in the upper edge of the lever of shift-key 56, and normally holds the lever of key 56 and the lever 61 in aligned position through the abutment of an ear 65 on the lever 61 striking against the under edge of the lever of shift-key 56. When the lever of key 56 is depressed, the lever 61 is carried along with it and both are restored by the spring 57', but, when the lever 61 is depressed, the initial motion will flex the spring 63 and the lever will turn about the stud 62 until an upright finger 66 bears against the rear face of the stop-plate 59. From this point to the end of the stroke, a down movement of the lever 61 will depress the key 56 until the movable stop element 45 strikes the stationary stop 46 to complete the carriage-shifting movement. At this point the upper edge of the finger 66 has almost passed under the lower edge of the stop-plate 59, and with a little extra pressure on the lever 61 will spring the parts sufficiently to pass the end of the finger 66 under the stop until the movement is arrested by an ear 67 striking the upper adjacent edge of the key 56. This effectually locks the stop element 45 against the stop 46 for an indefinite period, which is desirable when the character of the work calls for a continuous use of capital letters. When it is desired to return to normal printing, the depression of the key 56 beyond the position fixed by the lever 61 will relieve the tension of the finger 66 against the stop 59, and permit the spring 63 to restore said lever 61, and both levers will return to normal position under the tension of the spring 57'.

To properly adjust the co-operation of the finger 66 to the stop-plate 59, the latter may be adjustably secured to the front comb 60 by screws 60'. A portable machine is usually provided with a carrying case within which the machine fits snugly, and without any loss of space, and, as the carriage is always wider than the frame of the machine with carriage rails of equal length on the frame, it is necessary that the carriage be adjusted to a central position relative to the base and frame before inserting the machine into its case. To promote a quick and accurate alignment of the carriage prior to its being placed in the carrying case, indicated in Figure 2 by dot-and-dash lines at C, a locking lever 68 is pivotally hung from a projecting part of the frame 16' and provided with a finger-button 69 and a detent 70 to co-operate with a detent-

spring 71 to hold said lever against a stoppin 72 in one position, or at a forward position where an outstanding finger 73 formed on the lever enters a slot 74 in the edge of a shift-frame carriage-rail 75. In this position a similar slot 76 in the moving front carriage-rail 77 aligns with the slot 74, so that the carriage assumes a central position with relation to the frame 16'. Due to the fact that the tongue enters both slots in the rails, and is spring-pressed therein, the carriage is effectually prevented from shifting longitudinally or vertically. Furthermore, the locking lever 68 functions as a carriage-position locator, that is, by throwing said lever forwardly, so that the detent 70 is under tension of the spring 71 and the finger 73 bears against the carriage-rail 77, the carriage may be shifted from any position laterally along the rails until the slot 76 of the carriage-rail registers with the finger, at which time the finger will be projected into said slot 76, due to action of the spring 71, thus simultaneously locating the proper position of the carriage and locking the same against accidental movement in all directions.

No claim is herein made to features which are common to this application and my co-pending application No. 148,286. The claims in this case are limited to features which are not disclosed in said application 148,286.

Variations may be resorted to within the scope of the invention, and portions of the improvements may be used without others.

Having thus described my invention, I claim:

1. In a typewriting machine, the combination with a main frame and a case-shift frame mounted for movement therein, of a pair of brackets mounted adjacent the lower side edges of the main frame, said brackets extending under the edges of the shift-frame and provided at their free ends with rollers arranged to contact with the inner walls of said shift-frame to brace the same against vibrational movement and provide guiding means therefor during shifting operations.

2. In a typewriting machine, the combination with a main frame and a case-shift frame mounted for movement therein, of brackets carried by the main frame, said brackets extending under the sides of the shift-frame and having means contacting with the inner sides of said shift-frame to guide the same during shifting operations.

3. In a typewriting machine, the combination with a main frame, a case-shift frame including a pair of side plates, each having a slot adjacent its lower edge, a pair of swingable connections between the main frame and the side plates, and a pin carried by the free end of each of said connections, to engage the slot, of locking members pivoted for movement on the side plates, said locking members each having a slot arranged to re-

- ceive the pin carried by the adjacent connection, said slot in each locking member directed at right angles to said first-mentioned slot to pivotally secure the pin to its adjacent side plate, and means for holding each locking member into or out of engagement with said pin, the locking members, when unlocked, permitting the whole carriage structure to be bodily removed from the machine.
4. In a typewriting machine, the combination with a main frame, a case-shift frame including a pair of side plates, each having a slot adjacent its lower edge, a pair of swingable connections between the main frame and the side plates, and a pin carried by the free end of each of said connections, to engage the slot of locking members pivoted for movement on the side plates, said locking members each having a slot arranged to receive the pin carried by the adjacent connection, said slot in each locking member directed at right angles to said first-mentioned slot to pivotally secure the pin to the adjacent side plate, said locking members each having an arcuate slot arranged around its pivotal point, and a set-screw passing through said slot into the adjacent side plate to provide a limiting stop for said locking member when swung from one position to another, and to hold said member in either of said positions.
5. In a typewriting machine, the combination with a main frame, a case-shift frame including a pair of side plates, each having a slot adjacent its lower edge, a pair of swingable connections between the main frame and the side plates, and a pin in the free end of each of said connections to engage the slot of locking members pivoted for movement on the side plates, said locking members each having a slot arranged to engage the adjacent pin, said slot in the locking members directed at right angles to said first-mentioned slot to pivotally secure the pin to the adjacent side plate, said locking members each having an arcuate slot arranged around its pivotal point, and a set-screw passing through said slot into the adjacent side plate to provide a limiting stop for the locking member when swung from one position to another, and to hold said member in either of said positions, said locking members each provided on its upper edge with an ear bent over to provide a finger-piece for adjusting the positions of said locking member.
6. In a typewriting machine, a main frame, a case-shift frame, a connection link pivoted at one end to the main frame, the other end of said link provided with a pin connection to said case-shift frame, a roller upon the pin, and a case-shift lever fulcrumed for movement on the main frame, said lever including an end formed with a camming face to contact with the roller and impart motion to the case-shift frame.
7. In a typewriting machine, a main frame, a case-shift frame, a pair of connections between the frames to move the shift frame rearwardly as it is moved upwardly, one end of each of said connections including a pin connection to said case-shift frame, and a case-shift lever fulcrumed for movement on the main frame, said lever acting against the pin connection to lift the case-shift frame while permitting said pin connection to change its position upon said lever.

ALFRED G. F. KUROWSKI.
